CLAIM

The ornamental design for a teller counter, as shown and described.

DESCRIPTION

FIG. 1 is a top plan view of a single station teller counter;

FIG. 2 is a front elevation view of the teller counter of FIG. 1;

FIG. 3 is a rear elevation view of the teller counter; and

FIG. 4 is a side elevation view of the teller counter. The side of the teller counter not shown is a mirror image of the side shown in FIG. 4.
